CONRAD JOBST, OF TOLEDO, OHIO, ASSIGNOR TO THE AMES-BONNER COMPANY, OF
TOLEDO, OHIO, A CORPORATION OF MICHIGAN.

BRUSH-MAKING MACHINE.

1,303,907.

Specification of Letters Patent. Patented May 20, 1919.

Application filed August 23, 1917. Serial No. 187,821.

To all whom it may concern:

Be it known that I, CONRAD JOBST, a citizen of the United States, and a resident of Toledo, in the county of Lucas and State of 5 Ohio, have invented a certain new and useful Brush-Making Machine; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to brush making machines, and particularly to a machine adapted to bore bristle receiving holes in a brush-back and to set bristle tufts therein.

The object of my invention is the provision of a machine of the character described, which is more particularly intended for making tooth brushes, but is not restricted thereto, and is semi-automatic in its operation, automatically stopping when a pre- 20 determined number of holes have been bored in one brush-back and the holes in another back have been filled with bristle tufts, the operating parts thereof then automatically returning to normal starting position upon 25 the tripping of a manual control.

30 The invention is fully described in the following specification, and while, in its broader aspect, it is capable of embodiment in numerous forms, a preferred embodiment 35 thereof is illustrated in the accompanying drawings, in which—

Figure 1 is a side elevation of a machine embodying the invention with parts broken away. Fig. 2 is a similar view of a different 40 side thereof with the drill head carrying arm broken away. Fig. 3 is an enlarged sectional elevation taken on the dotted line 3—3 in Fig. 2, with parts broken away. Fig. 4 is a cross-section taken on the line 4—4 45 in Fig. 3. Fig. 5 is a top plan view of the machine with a part in section on the line 5—5 in Fig. 2. Fig. 6 is a fragmentary section on the line 6—6 in Fig. 3, and Fig. 7 is a perspective view of one of the brush- 50 back clamping units with parts broken away.

Referring to the drawings, 1 designates the machine frame, from one side of which an L-shaped arm 2 projects outward and upward. A table or slide-plate 3 is mount-

ed on the upper end of the arm 2 for horizontal reciprocatory movements toward and away from the upper end portion of the frame 1 and has its inner end, or that which is adjacent to the frame 1, provided with 60 vertically disposed cross-arms, one of which is designated 4, and projects upward and the other of which is designated 5 and projects downward from the table end. The upper arm 4 is of dove-tail form to form a 65 vertical retaining guide on which a plate 6 is mounted for vertical reciprocatory movements, the vertical movements being controlled as hereinafter described. The plate 6 is provided adjacent to its upper edge 70 and at the side thereof opposed to the arm 4 with a horizontally extending cross-guide 7, on which an article carrying plate 8 is mounted for horizontal reciprocatory movements with the article carrying face of said 75 plate disposed in a vertical plane. A brush-back clamping unit 9 is carried by the plate 8 on its outer vertical side or the side thereof adjacent to the upper end portion of the frame 1. The clamping unit which I have 80 shown for this purpose is illustrated in Fig. 7 and comprises a box member 10, which is bolted or otherwise suitably fixed to the plate 8 and contains a pair of blocks 11 and 12, which are mounted for relative to and 85 fro movements, and each of these blocks is provided with a work clamping jaw 13. The work clamping and releasing movements of the blocks 11 and 12 are controlled by a hand-screw 14, which extends vertically 90 through the box 10, being anchored against longitudinal movements relative thereto and having right hand thread connection with one of the blocks and left hand thread connection with the other thereof. 95

An adjustable end stop 15 is provided at one end of the box 10 for contact with one end of a brush-back to be clamped. The plate 8 has an arm or extension 16 of rearwardly angled L-form, which carries a 100 work clamping unit 17, which may be of the same construction as the clamping unit 9. A bracket-arm 18 projects outward and upward from one side of the frame-arm 2 adjacent to the upper end thereof and carries 105 at its outer end a drill-head 19 in advance of the clamping unit 17 in position for the drill of such head to bore horizontal holes in a brush-back a carried by said unit when the unit is moved forward toward the drill- 110

head. The thrust of the drill against the work is opposed by a thrust member 20, which is adjustably carried by a bracket-arm 21 at the rear of the arm 16 in sliding 5 thrust contact therewith in opposition to the side thereof carrying the clamping unit 17. The bracket arm 21 is carried by and projects from the slide-table 3.

- The lower arm 5 of the slide-table 3 has a 10 stub-shaft 22 fixedly projecting forward therefrom or toward the frame 1, and mounted for rotary movements on this shaft is a hub member 23, which fixedly carries an index-wheel 24 having ratchet- 15 teeth around its periphery, and the two pattern-wheels 25 and 26 disposed at opposite sides of the index-wheel 24. The pattern-wheel 25 controls the vertical movements of the plates 6 and 8 and for such 20 purpose the periphery of such wheel is suitably fashioned, as illustrated in Fig. 3, and the plate 6 has a spindle projecting therefrom and carrying a roller 27, which rides on the top of the wheel periphery (Fig. 6). 25 The pattern-wheel 26 is intended to control the horizontal movements of the plate 8 and for such purpose has its periphery suitably fashioned in accordance with the movement desired and in contact with a roller on the 30 lower end of a vertically disposed lever 28, which is fulcrumed at 29 to the forward end of the slide-table 3 and has its upper arm 30 extending upward at the rear of the plate 8 and provided at its end with a roller 31 in 35 horizontal thrust contact with a thrust shoulder 32 on the upper edge of the plate 8. The thrust of the roller 31 on the shoulder 32, in the present instance, is toward the left and a movement of the plate 8 under such 40 thrust is resisted by a coiled contractile spring 33, which connects the right end of the plate 8 to a bracket-arm 34 projecting horizontally from the vertically movable slide-plate 6 at the right thereof.
- 45 An angled lever 35 is fulcrumed to the table-arm 5 below the index-wheel 24, as at 36, for vertical rocking movements and has one arm thereof pivotally carrying a pawl 37 in engagement with the teeth of the index-wheel and its other arm extending horizontally and provided with a roller 38, which, at each rearward movement of the table 3 and arm 5, travels up an incline 39 (Figs. 2 and 4) on the frame-arm 2 and 50 effects a rocking of such lever in a direction to impart a predetermined rotary movement to the index-wheel. The pawl 37 is held in yielding engagement with the teeth of the index-wheel by a spring 40.
- 55 The main drive-shaft 41 of the machine is mounted transversely in the frame 1 and, in the present instance, carries at one end thereof a loose belt-pulley 42, which is driven from any suitable source of power, 60 and a clutch member 43, which is feath-

ered to the shaft and movable into and out of clutch engagement with the pulley 42. The shipper-lever 44 for the clutch member has its upper end pivoted to a link 45, which projects horizontally into the interior of the frame 1 and has its inner end mounted for limited horizontal movements on a pin 46. A coiled contractile spring 47 acts on the shipper-lever 44 to normally hold it in clutch released position. The link 45 75 has a shoulder 48 on one side thereof with which a vertically disposed rocker-arm 49 on a shaft 49' is intended to have thrust engagement in opposition to the spring 47 when rocked in one direction. An arm 50 80 projects horizontally from the shaft 49' and is pivoted at its outer end to a foot trip 51, which is guided for vertical movements by the frame 1 and has its lower end angled to provide a foot engaging part. A coiled 85 contractile spring 52 normally retains the trip in raised position. Upon a depression of the trip the arm 49 is rocked in a direction to impart a clutch engaging movement to the link 45 and shipper-lever 44.

The other end of the shaft 41 to that which carries the pulley 42 has crank connection through a link 53 with a vertically disposed lever 54, which is pivoted at its lower end to the adjacent side of the frame 1 and has its upper end projecting up into the head portion 1^a of the frame 1 and connected to the bristle tuft setting plunger of the tuft setting mechanism, the head of which is designated 55, to operate said mechanism, as is well understood in the art, and as more specifically illustrated and described in connection with my former Patent No. 1,144,711. It will be understood that at each forward movement of the lever 54 the bristle tuft setting mechanism is operated to set a bristle tuft in the registering hole of a brush-back which is carried by the clamping unit 9.

A vertically disposed lever 56 is fulcrumed to the rear side of the frame-arm 2 and has its upper end pivotally connected to the slide-table 3 and its lower end connected by a link 57 to the lever 54, whereby each rearward bristle tuft setting stroke of the lever 54 will impart a predetermined forward movement to the table 3 to place a brush-back, carried by the plate 8 in tuft receiving position. The rearward thrust of the link 57 on the lever 56 is cushioned by a spring-pressed thrust member 58.

A coiled tension spring 59 is disposed within a portion of the hub member 23 and connected to said hub member and the stub-shaft 22 in a manner to effect a normal back turning of the index and pattern-wheels 24, 25 and 26. A stop 60 on the outer marginal portion of the index-wheel coacts with one end of a trip-lever 61 to limit the back turning movement of said wheels (Fig. 3). The lever 61 is horizon- 130

- tally disposed, being fulcrumed on a stud 62 projecting forward from the lower end portion of the table-arm 5. The arm of the lever 61 with which the stop 60 coacts 5 extends over a pin 63 on a side of the pawl 37 in position to coact with said pin and retract the pawl 37 from engagement with the index-wheel teeth when said lever is rocked in one direction. A spring-pressed 10 dog 64 normally engages a tooth in the index-wheel 24 and prevents a back turning of such wheel. This dog has a pin 65 projecting transversely therefrom below the lever 61 in position for the lever, when 15 rocked in one direction, to coact therewith and effect a retraction of the dog from wheel engaging position.
- A trip-rod 66 is mounted for vertical reciprocatory movements in the frame-arm 20 2 and has a pin 67, which, when the rod is raised, coacts with one end portion of the lever 61 and effects a downward rocking of the other end portion thereof to retract both the pawl 37 and dog 64 from index-wheel 25 engaging position so that the wheel is then free to be returned to its normal or starting position by the action of the spring 59. The lower end of the trip-rod 66 rests on the rear end of a pedal-lever 68, which is 30 pivoted to one side of the frame 1, as at 69, and has its forward end disposed in position to be depressed by a foot of the operator. The upper end of the trip-rod 66 is provided with a trip-finger 70, which, upon 35 a raising thereof, engages an arm 71 projecting from the lever 28, 30 at the fulcrum thereof. A raising of the finger 70 in engagement with the lever-arm 71 effects a rocking of the lever 28, 30 to disengage the 40 pattern-wheel 26 and to force the work carrying plate 8 to the left to starting position against the tension of the spring 33.
- The vertical slide-plate 6 has an arm 72 fixedly projecting from one side edge there- 45 of in position to be engaged and raised by the finger 70 when elevated with the trip-rod 66, thus raising the roller 27 from engagement with the periphery of the pattern-wheel 25.
- 50 An arm 73 fixedly depends from one end of the shaft 49' and has its lower end angled to engage a notch in a catch member 74 projecting from one end of a trip-lever 75. This lever is fulcrumed to the frame-arm, 55 as at 76, and has its inner end provided with a pin 78 in position to be engaged by an ear 79 on the outer marginal portion of the index-wheel 24 when such wheel has been turned a predetermined extent for 60 such purpose. The engaging of the ear 79 with the pin 78 causes a rocking of the lever 75 to release the catch engagement of the member 74 with the arm 73, thus permitting a rocking of the shaft 49' in a direction to 65 permit the spring 47 to withdraw the clutch 43 from pulley engaging position, thus stopping the operation of the machine. The shaft 76 has a control arm 80 rising therefrom to facilitate a manual movement of the trip-lever 75 to stop the running of the 70 machine whenever desired. A coiled contractile spring 81 connects the arms 73 and 80 and acts to retain the catch-member 74 and arm 73 in catch engagement.
- The operation of the machine is as fol- 75 lows: The operator, having positioned in the clamping unit 17 a brush-back *a* to be bored and positioned in the clamping unit 9 a bored brush-back *b*, depresses the trip 51 which rocks the shaft 49' and effects an outward movement of the link 45 and shipper-lever 44 to place the clutch member 43 in pulley engaging position, the clutch means being maintained in such engaged position by the catch engagement of the arm 73 80 with the notched end of the catch-member 74. At each revolution of the shaft 41 the lever 54 has a forward and return stroke imparted thereto to move the slide-table 3 first forward and then backward, the boring 85 of the first hole in the brush-back *a* and the setting of a bristle tuft into the first hole of a brush-back *b* taking place during the forward stroke of said table. The bristle tuft is ejected from the bristle feeding head 55 upon the rearward movement of the lever 54. Upon the rearward or return stroke 90 of the table 3 after the said boring and bristle feeding operations the roller 38 on the lever 35 travels up the incline 39, effecting a rocking of said lever and a consequent predetermined index-wheel feeding movement to the pawl 37. This movement of the index-wheel 24 and the pattern-wheel 26, which rotates therewith, permits a sufficient 95 rocking of the lever 28, 30 and movement to the right of the slide-plate 8, under the action of the spring 33, to place the brush-back *a* in position for the next hole to be bored therein and the brush-back *b* in position 100 for the next hole in order therein to receive a bristle tuft. The boring and bristle tuft filling operations of the respective brush-backs then take place upon the next rearward stroke of the lever 54 and forward stroke of the table 3. When a horizontal row of holes has been bored in one brush-back and a corresponding row of holes in the other brush-back filled with bristle tufts the pattern-wheel 25 will have rotated a sufficient extent to raise the slide-plates 6 and 8 a distance equal to the space between the rows of holes, and the first hole of the second row will be bored in one brush-back and filled in the other brush-back upon the next 105 forward stroke of the table 3. The boring and filling of the successive holes in the rows of the respective brush-backs will then take place the same as before except that the slide-plate 8 is moved in the opposite direc- 110 115 120 125 130

tion to the direction in which it was moved for the first row, such movement being effected by the coöperating action of the wheel 26 and lever 28, 30. When the boring of one and 5 the bristle filling of the other brush-back has been completed the ear 79 on the index-wheel 24 will have moved into position to engage the pin 78 and impart a tripping movement to the lever 75 to release the 10 catch engagement of the member 74 with the arm 73. The shaft 49' then rocks to release the thrust engagement of the arm 49 with the link 45 so that the clutch 43 will be drawn from pulley engaging position by 15 the action of the spring 47. The operator then depresses the forward end of the pedal-lever 68 to effect a raising of the trip-rod 66 so that the finger 70 thereon engages the arm 72 and raises it and the slide 6 a sufficient extent to release the roller 27 from engagement with the pattern-wheel 25. The 20 raising of the finger 70 also causes it to coact with the arm 71 and rock the lever 28, 30 to disengage the pattern-wheel 26 and to 25 move the slide-plate 8 to starting position against the tension of the spring 33. The raising of the trip-rod 66 also causes the pin 67 to coact with and rock the lever 61 to withdraw both the pawl 87 and dog 64 from 30 index-wheel engaging position. When the wheels 24, 25 and 26 have thus been released the spring 59 will cause a return thereof to normal starting position, which is determined by the stop 60 striking the adjacent 35 end of the lever 61. The operator then removes the brush-backs from their respective clamps and places the bored brush-back in the clamp 9 and an unbored brush-back in the clamp 17 preparatory to again starting 40 the machine to bore one and set bristle tufts in the other back.

It is evident that the machine is semi-automatic in its nature in that the operator, after having placed the brush-back in position 45 and started an operation of the machine, can leave the machine and it will be automatically stopped when the boring and filling operations in the respective brush-backs have been completed. A single operator is 50 thus enabled to take care of a number of machines at one time. The semi-automatic returning of the machine parts to normal or starting position by merely tripping the 55 pedal-lever 68 facilitates the operation of the machine and enables the parts to be easily and quickly returned to starting position after the completion of the boring and filling of the brush-backs mounted on the plate 8.

60 While I have herein shown and described one specific embodiment of my invention for illustrative purposes and have disclosed and discussed in detail the construction and arrangement incident to such specific embodiment 65 thereof, it is to be understood that the

invention is not limited to the mere detail or relative arrangement of the parts, but that deviations from the illustrated form or embodiment of the invention may be made without departing from the spirit of the 70 claims.

Having thus described my invention, what I claim as new, and desire to secure by Letters Patent, is—

1. In a machine of the class described, an 75 article carrying member mounted for horizontal and vertical reciprocatory movements, two pattern wheels, a roller carried by said member and resting on one of said pattern wheels for imparting predetermined 80 vertical movements to the member when the wheel is rotated, means yieldingly urging a horizontal movement of said member in one direction, means connecting said other pattern wheel and member for coöperating 85 with said yielding means to control and effect predetermined horizontal movements to said member, means operable to impart rotary movements to said wheels, and manually controlled means operable to engage 90 and vertically move said member to raise its roller from engagement with said first pattern wheel and to engage the means connecting said second pattern wheel and member to move said means out of engagement 95 with its pattern wheel and to return the member to an initial point in its horizontal movement.

2. In a machine of the class described, an 100 article holding member mounted for horizontal and vertical reciprocatory movements, two pattern wheels, means for rotating said wheels, an element carried by said member and resting on one of said wheels to control the vertical movements of the member when the wheel is rotated, a lever connecting the other of said wheels and member to impart horizontal movements to the member in one direction from a rotation of the wheel and to control the movements of the 110 member in the other direction, means urging a movement of said member in said other direction, and trip means operable to engage said lever and move it out of engagement with its operating wheel and into position to return the member to its starting position and to raise said member from operating relation to said first pattern wheel.

3. In a machine of the class described, a 115 vertically movable article carrying member, a pattern member for controlling the vertical movements of said first member, pawl and ratchet means operable to periodically move said pattern member in one direction, a dog engaging the ratchet part of said means to prevent a back movement of the pattern member, means operable to release the engagement of the pawl and ratchet parts of said first means and to move said dog to released position, and means for automatically 120 125 130

backturning said pattern member to starting position when released for back movement.

4. In a machine of the class described, an article carrying member mounted for vertical reciprocatory movement, means operable to impart said reciprocatory movement to said member, a manually controlled trip-rod mounted for reciprocatory movements, and trip means for coöperating with said rod at a predetermined point in the reciprocatory movement thereof to move said member to disconnect it from said operating means.

5. In a machine of the class described, a work carrying member mounted for predetermined movements, means operable to impart said predetermined movements to said member, drive means operable to periodically move said first means, a trip-rod mounted for longitudinal reciprocatory movements and adapted at predetermined points in its movement to break the operating connection between said first means and member and the driving connection between said first and second means.

6. In a machine of the class described, a frame, a work carrying member mounted for predetermined reciprocatory movements relative to said frame, means operable to impart said predetermined movements to said member and including an index-wheel, a pair of pawls engaging said wheel, one serving as a back-check and the other being operable to impart advancing movements to the wheel, a lever movable to disengage said pawls from said wheel, a trip-rod mounted for longitudinal reciprocatory movements in said frame and operable when moved to move said lever and to break the operating connection between said member and operating means.

7. In a machine of the class described, a work-holding member mounted for predetermined reciprocatory movements, a pattern wheel, a lever connecting said pattern wheel and member for imparting predetermined movements from one to the other, means for driving said pattern wheel including a pawl and ratchet, a dog coacting with the ratchet member of said driving means to prevent a back turning of the ratchet member, a lever operable to disengage the pawl member of said driving means and

said dog from the ratchet member of said means, and trip means operable to act on said pattern wheel coacting lever to break the connection therebetween and on said second lever to disengage the dog and the pawl member from the ratchet member of the driving means.

8. In a machine of the class described, a table mounted for horizontal reciprocatory movements, a work holder carried by said table for vertical and horizontal reciprocatory movements relative thereto, two pattern wheels, means for driving said pattern wheels, means carried by said holder and resting on one pattern wheel to coöperate therewith to impart vertical movements to the holder when the pattern wheel is rotated, means connecting the other pattern wheel and holder to impart predetermined horizontal movements to the work holder from a rotation of the coacting pattern wheel, a trip member operable to engage said work holder and move it to separate one of said means and coacting pattern wheel and to coact with the other of said means to move it from engagement with its pattern wheel and to impart a predetermined horizontal movement to the work-holder, and means for imparting rotation to said pattern wheels.

9. In a machine of the class described, a frame having an incline, a table mounted for horizontal reciprocatory movements on said frame, a work holder movably carried by said table, a pattern wheel and a ratchet wheel fixed to each other and rotatably carried by said table, a connection between said pattern wheel and work holder to impart predetermined movements to the work holder from a rotation of said wheel, a lever fulcrumed to said table, and adapted to coact with and be rocked by said frame incline during a predetermined portion of the table movement, a pawl carried by said lever and operable to coact with said ratchet wheel and impart rotation thereto when the lever is rocked by said incline, and means for periodically imparting reciprocatory movements to said table.

In testimony whereof, I have hereunto signed my name to this specification.

CONRAD JOBST.
